Thomas Bond Rogerson, INVENTOR
By Heddersheim Fairbanks, ATTORNEYS

UNITED STATES PATENT OFFICE.

THOMAS BOND ROGERSON, OF GLASGOW, SCOTLAND.

COGGING AND ROLLING MILL FOR IRON AND STEEL.

Application filed March 5, 1921. Serial No. 450,054.

(GRANTED UNDER THE PROVISIONS OF THE ACT OF MARCH 3, 1921, 41 STAT. L., 1313.)

To all whom it may concern:

Be it known that I, THOMAS BOND ROGERSON, of East Thorne, Tollcross, Glasgow, Scotland, a British subject, have invented 5 certain new and useful Improvements in Cogging and Rolling Mills for Iron and Steel, of which the following is a specification.

At present with iron or steel cogging and 10 rolling mills it is usual to have the rolls carried in housings and to drive them, through coupling spindles, by means of gear pinions which, in turn, are driven by the engine. The pinions are usually made of cast steel 15 with helical teeth and in some cases these are cut. When a breakage occurs the pinions are expensive to replace and sometimes considerable time is lost in their replacement during which the mill has to stand 20 idle.

The object of the present invention is to dispense with the usual expensive helical pinions employed in iron or steel cogging and rolling mills and to provide an improved friction drive in lieu thereof.

Under this invention I employ cast iron or steel driving pinions of considerable weight and without teeth but arranged above and in frictional contact with one 30 another and operatively connected, by suitable coupling spindles, with the mill rolls, one of the pinions being driven, in the usual manner, from the engine shaft. The lower pinion is preferably driven whilst the other 35 pinion is free to bear by gravity thereon.

The invention can be applied to both two and three high mills.

On the annexed drawings I have shown 40 my improved friction drive, simply by way of illustration or example, as applied to roughing rolls.

Fig. 1 is an elevation of the rolls and drive and Fig. 2 is an end view of the driving pinions.

45 A, A¹, represent the roughing rolls turnably supported in housings B, B, fixed on a suitable base C.

Under this invention the rolls A, A¹, are driven by toothless friction pinions D, D¹, 50 through suitable coupling spindles E, E¹, the pinions being turnably supported one above the other in housings F, F. The lower pinion D¹ is coupled to the engine or driving shaft G and the upper pinion D is

arranged to bear by gravity on the lower 55 pinion D¹. To this end the contact surfaces of the side bearing blocks H, H for the upper pinion D are made straight and parallel to permit vertical movement of the upper pinion so as to ensure that it will rest freely 60 on the lower pinion.

The driving pinions are made of cast iron or steel turned in a lathe to the proper size and, as will be understood they are of considerable weight and drive by surface friction. 65 In practice I find that they last much longer than ordinary toothed pinions and, in work, obviate the usual shocks to the engine. Each pinion D, D¹, is about half the weight and has a length of tread approximately two-fifths that of one of the driven rolls A or A¹.

The improved drive eliminates all danger 70 of breakage to the roll housings and to the rolls and mill engine, which might otherwise occur, for example, by a plate running into the necks of the rolls in a plate mill, or of a collar in a section mill. The drive also prolongs the life of the rolls, which are expensive, because it is far smoother than the 75 toothed gearing used heretofore, and a regular surface speed throughout all operations is easily obtained. Finally there is a considerable saving in oil and grease due to the absence of toothed gearing.

80 Friction wheels have heretofore been employed in many forms and for many purposes; but so far as I am aware heavy friction driving pinions, made without teeth, have never before been used in rolling mills 85 as herein described and with the advantages 90 stated.

Having now fully described my invention 95 what I claim and desire to secure by Letters Patent is:—

1. In an iron or steel cogging or rolling mill the combination with the mill rolls of friction driving means comprising a housing, heavy toothless driving pinions one for each roll mounted one above another in constant frictional contact at all times in said housing, a coupling between each pinion and its roll, and means for connecting one of the pinions with a suitable driving source.

2. In an iron or steel rolling or cogging mill, the combination with the mill rolls of friction driving means comprising a housing, heavy toothless driving pinions, one

for each roll, mounted one upon the other in said housing, and in constant frictional contact at all times, said toothless pinions being each approximately half the weight and ⁵ two-fifths the length of its roll, a coupling between each pinion and its roll, and means for connecting one of the pinions with a suitable driving source.

3. In an iron or steel rolling or cogging mill, the combination with the mill rolls of friction driving means comprising a housing, a pair of heavy toothless driving pinions, one for each roll, mounted one upon another in said housing, the upper pinion

being free to move vertically and bearing ¹⁵ freely by gravity on the lower one, a coupling between each toothless pinion and its roll and remaining constantly in contact therewith at all times, and means for connecting the lower pinion with a suitable ²⁰ driving source.

In testimony whereof I affix my signature in presence of two witnesses.

T. B. ROGERSON.
